UNITED STATES PATENT OFFICE.

WILLIAM ISRAEL LITTMAN, OF BROOKLYN, NEW YORK.

SHOE HEEL.

Application filed July 23, 1925. Serial No. 45,531.

This invention relates to shoe heels and has particular reference to heels of the detachable or removable type.

In the use of a shoe, the thread or tap of the heel which is generally formed of leather or rubber, wears both rapidly and unevenly, thereby requiring premature replacement of the tap, or in some instances the entire heel. The practice of scraping the tap or complete heel, however, when only a small portion thereof has become worn results in an enormous waste of material, and naturally increases the expense in the upkeep of the shoe. It has been proposed heretofore to provide the heel with a removable tap which can be readily attached and detached when desired so as to replace the relatively small worn portion without disturbing the unaffected body of the heel. Previously known removable heels, however, have fallen short of commercial success due to important structural disadvantages, among the most noticeable of which are complexity of construction, inefficiency in use, and prohibitive expense of manufacture.

A general object of this invention is to provide an improved heel of this removable type in which the disadvantages are mentioned.

A further object of the invention resides in the provision of an improved heel having a tap which may be attached to and removed from the body of the heel by an unskilled person without requiring special tools or attaching means.

A further object of this invention resides in the provision of a one-piece rubber heel tap which is retained upon the heel by a locking pin entirely concealed within the body of the heel.

For a more complete understanding of this invention together with further objects and advantageous details and construction, reference may be had to the accompanying drawings illustrating an embodiment in which:

Figure 1 is a section through the heel illustrating the removable tap in position thereon.

Figure 2 is a bottom view of the heel with the tap removed.

Figure 3 is a perspective of the improved tap; and

Figure 4 is a perspective of the reinforcing member with which the tap may be equipped.

Referring more particularly to the drawings, 2 indicates a heel which may be of any preferred size or design, the French type

shown being selected for illustrative purposes only. Permanently secured to the bottom of the heel by means of screws 4 is a metallic plate 6 which in size and contour corresponds to the heel bottom. The plate 6 is formed with a downwardly extending peripheral wall 8, the latter being provided with an inturned flange 10 as illustrated clearly in Figure 1. The wall 8 and flange 10 extend completely around the heel with the exception of the front face which is left unobstructed. The bottom face of the heel plate, the side wall and the inturned flange form a seat or slideway for the reception of a heel tap 12 hereinafter described in detail.

The heel tap 12 is preferably formed from a rubber compound which is used in the ordinary rubber heels, although leather or similar material may be used if desired. The tap is made in one piece and consists of a relatively thick tread portion 14 and an upper portion 16. The upper portion 16 is thinner and somewhat smaller in diameter than the lower tread portion, and in general is of such dimensions as to snugly fit within the seat formed on the heel plate. The tap is provided with a peripheral groove 18 between the upper and lower portions thereof, the groove being adapted to slidably receive the flange 10 therein in a manner clearly understood. While it has been proved that a plain groove in the heel tap such as 18, is ordinarily sufficient, a channelled reinforcing member 20 may be embedded in the groove, if desired, in order to give additional rigidity to the heel tap, and by affording a metal to metal contact with the flange 10 facilitate the shoving of the heel tap into and out of position.

The interlocking connection between the tap and the heel plate afforded by the flange and groove serves to retain the heel tap in position against upward, downward, sideward, and rearward thrust. It will be apparent, however, that in so far as the heel plate is concerned the tap is free to slide out of its seat by a forward movement upon the application of sufficient force. The means for locking the heel tap against forward movement will now be described.

The heel body 2 is provided adjacent its bottom face with a recess or bore 22 within which is slidably mounted a locking pin 24. The locking pin consists of an enlarged head 26 which is preferably loaded or weighted, and a reduced shank 28. The

shank of the locking pin is adapted to extend through an opening 30 formed in the heel plate beneath the bore 22, the opening 30 being smaller in diameter than the head 5 of the locking pin, whereby the latter is prevented from completely falling from the bore 22. The heel tap 12 is provided on its upper face with a bore or recess 32 which is adapted to register with the opening 30 in the heel plate and receive the shank of the locking pin when the tap is in a seated position. In order to facilitate the entrance of the locking pin within the tap bore, the mouth of the latter is slightly tapered as 15 at 32.

The locking pin is retained within the bore in the heel tap by gravity and serves to effectually lock the tap against displacement from its seat during use. When it is desired 20 to remove the tap for replacement or to interchange with the tap on the other shoe, the heel is simply turned over, thereby causing the locking pin to fall out of the bore in the heel tap. Being thus released, the tap 25 may be removed by sliding the same toward the front until the flange of the heel plate becomes disengaged from the groove 18 in the tap. Upon the insertion of a new tap, the shoe is turned back to normal position 30 and the locking pin immediately falls into the bore 32 of the tap in the manner previously described.

In order to prevent the lower end of the locking pin from catching upon the edges

of the opening in the heel plate, the pin is 35 constructed a trifle larger than the bore 22 in the heel so that when the shoe is reversed to move the locking pin into releasing position, the lower end of the pin will lie between the top and bottom face of the heel plate. Accordingly, the lower end of the locking pin 40 in the position of release is entirely disconnected with the heel tap but never passes beyond the upper face of the heel plate.

It will be noted that the improved heel 45 tap disclosed consists of a minimum number of parts, which may be formed in a single molding operation. When the metallic reinforcing element is used the manufacture of the tap is not materially complicated as the 50 reinforcing element is simply placed in position and pressed into place during the molding of the tap.

Having described my invention, what I claim as new and desire to secure by Letters Patent of the United States is:

1. A heel tap having a peripheral groove in the side wall thereof and a U-shaped metallic member embedded within said groove.

2. A heel tap comprising a body portion 60 of resilient material, the sides of said body being provided with a groove lying wholly between the upper and lower faces of the body, and a U-shaped metallic member embedded within said groove.

In testimony whereof I affix my signature.

WILLIAM ISRAEL LITTMAN.
